UNITED STATES PATENT OFFICE

AUGUSTUS C. DURDIN, JR., OF CHICAGO, ILLINOIS

ELECTRIC SWITCH ACTUATING MECHANISM

Application filed August 6, 1928. Serial No. 297,907.

This invention relates to electric switch actuating mechanism and has for its principal object the provision of electric switch actuating mechanism for a plurality of electric switches operated alternately or in some other sequence by pressure or vacuum operated means which is made responsive to variation of pressure or vacuum in some part of a system employing pressure or vacuum in its operation. In many hydraulic systems, two (or more) electric motor driven pumps are employed one, at a time, for supplying water or other liquid to a tank or reservoir, to be drawn off as required. Ordinarily manually operated switches are employed for the motors, which switches require the services of an attendant. The practice is to operate one motor for some time and then the other, and thus distribute the wear. Sometimes a motor or pump becomes disabled and the other one is then available for use, and the service may be maintained despite the breakdown of one of the motors or pumps. Sometimes it requires the services of both pumps to handle the required amount of water or other liquid. Ordinarily the attendant is relied on to throw the switches and occasionally because of the neglect of the attendant the operation of the pump is not properly kept up.

In accordance with the present invention the switches for the motors are closed alternately by switch actuating mechanism operated by pressure means, responsive to variations of pressure or vacuum in the system, and both switches closed, in case of an emergency requiring the use of both pumps, the closed switch or switches being automatically opened when the pressure or vacuum has been restored to normal.

The invention consists in electric switch actuating mechanism embodying switch throwing mechanism operated by pressure or vacuum means responsive to variations of pressure or vacuum in the system with which the electric switch actuating mechanism is used. It further consists in electric switch actuating mechanism for operating two electric switches having switch throwing means constructed and arranged to close the switches alternately or in any other sequence,

when moved in one direction, and actuated by pressure or vacuum means responsive to variations of pressure in the system. It further consists in an electric switch mechanism as described in which the switch throwing means may close both switches if required. It further consists in the several novel features hereinafter fully set forth and claimed.

The invention is clearly illustrated in the drawings accompanying this specification, in which—

Figure 1 is a diagrammatic view illustrating a simple embodiment of the present invention;

Fig. 2 is a side elevation, partly broken out, of a form of variable stroke device which may be employed for obtaining the alternate action on the switches; and

Fig. 3 is a side elevation thereof looking in the direction of the arrow 3 in Fig. 2.

Referring to said drawings, which show the invention applied to a pneumatic water supply system, the reference character 4 designates a tank or reservoir for receiving and storing water or other liquid under pressure, and 5 designates an air pump connected thereto by a pipe 6, and adapted to supply pressure for raising the water or other liquid to the higher floors of a building in case the city pressure falls below normal.

Two electric motor driven water pump units A, B are shown in connection with the tank or reservoir 4. The inlets of the pumps a' b' thereof are connected to the main water supply pipe 7 and the discharge ends of the pumps are connected to the tank or reservoir 4, by discharge pipes 8. A pipe 9 is connected to the system described, and branch pipes convey water or liquid to the several places where water or other liquid is to be delivered. The electric motors which drive the pumps are illustrated at a, b, and together with the pumps a' b' comprise the electric motor driven pump units A, B which are preferably mounted on suitable bases, as shown.

When the mechanism forming the subject matter of this specification is used in connection with a pneumatic water supply system, a pressure operated device C is employed which

may be in the nature of a diaphragm device, a pressure operated piston or plunger device, a Bourdon tube device or other equivalent pressure operated device. For convenience, 5 a diaphragm device C of conventional form is shown, which is connected to the tank or reservoir 4 by an air pipe 10. The diaphragm c of the diaphragm device is connected to the lever c' of the device by a stem 10 c² as usual, and for convenience a weight c³, adjustably mounted on the lever, is employed for setting the diaphragm device to respond to its required pressure in the tank.

The electric switches for the pumps A, B 15 are shown at A', B', and are connected to the motors of the pumps by conductors a⁴, b⁴. The switches may be connected to the main line as shown. Connecting mechanism D is interposed between the pressure device C and 20 actuating levers a⁵, b⁵ of the switches A', B' for closing the switches alternately or in any other sequence (and for closing both if it becomes necessary for both pumps to operate) whenever the pressure within the tank falls 25 below a predetermined low point, and for opening the closed switch or switches whenever the pressure reaches a predetermined high point. In the form of the invention illustrated, said connecting mechanism 30 comprises connections between the pressure device C and each switch lever a⁵, b⁵ at least one of which embodies a variable stroke device constructed and arranged to permit the connections between the pressure device C and 35 switch levers to function alternately during the strokes which close the switches. The connections may comprise rods a⁶, b⁶ secured to the lever c' or other actuating member of the pressure device C engaging with the 40 switch levers as, for instance, through collars a⁷, a⁸, b⁷, b⁸ secured to the rods a⁶, b⁶. At least one of said rods has a variable stroke member D' therein which intermittently 45 renders said rod ineffective for closing the switch operated thereby, so that when ineffective for that purpose the other rod closes its associated switch when actuated in one direction by the pressure device.

A simple form of variable stroke member is 50 more fully shown and described in my prior Patent No. 1,666,873 of April 17, 1928. Briefly stated, the variable stroke member herein shown comprises a tubular element d' having a continuous groove d² in its wall, and disposed around the same, said groove having long sections d³ and short sections d⁴ opening into and joining with connecting sections d⁵ through oblique sections d⁶. Traveling in 55 said continuous groove is a pin or other traveling element d⁷ which, when it engages with the ends of the sections of the groove, connects the two elements whereby they travel together as a unit, but permitting lost motion of the traveling element d⁷ when moving 60 through the groove.

The rod b⁶ is made in two parts b^x, b^z of which the part b^x is rigidly secured to the tubular element d' and the part b^z is secured to the traveling element d⁷. When only one variable stroke member is used, the collars a⁸ 70 b⁸ on the two rods are set at such positions thereon that they will open the switches simultaneously (if each are closed) and the collar a⁷ on the rod a⁶ on the downward movement of the rods will engage and actuate the associated switch lever a⁵ before the collar b⁷ on the rod b⁶ engages its associated switch lever b⁵ whenever the traveling element d⁷ is 75 moving down through a long section of the continuous groove d² but not when said traveling element is traveling down a short section of said groove. Although if the rods are moved down further than necessary to actuate one switch, the inactive rod will also close its associated switch, the result being that when the rods descend, one of the rods closes its associated switch, and starts one motor and when the rods descend again the other rod will close its associated switch and start the other motor. 80 85 90

In the operation of the mechanism above described, in connection with a pneumatic water supply system, and assuming that the diaphragm device C is set to close a switch when the pressure in the system falls below 95 a predetermined point, and that a maximum amount of water is contained in the tank under the predetermined pressure, whenever sufficient water is drawn from the tank to lower the pressure therein below the predetermined low point, the diaphragm device lever c' swings down under the influence of the weight, draws the connections D down until one of the collars therein engages with 100 and swings down its associated switch lever 105 and closes that switch, thereby starting the pump motor of the associated pump, which continues to run, and supplies the tank with water until the pressure therein is again raised to normal. The diaphragm device is 110 again actuated when the pressure reaches its high point, the lever raised, and the connections D lifted until the collar thereof encounters the lever of the closed switch, shifts 115 the switch lever and opens the switch.

During the downward or closing movement of the connections D, the traveling element d⁷ has moved down through one of the long or short sections of the groove. If during the stroke just mentioned, it was traveling in 120 the long section, then it will move idly to the bottom thereof, and consequently the collar a⁷ on the rod a⁶ engages the lever a⁵ of the associated switch A' and closes the circuit to the motor of the pump designated A. The pump A continues to run until the pressure in the tank is again restored to normal, and as a consequence the diaphragm device is 125 actuated in a direction to lift the connections D until the collar a⁸ encounters the lever of 130

the switch which is closed, and swings the lever up, thereby opening the switch and stopping the motor of the pump A.

During said upward movement of the rod b^6 , the traveling element d^7 moves up through the long section of the continuous groove and into one of the connecting sections, and when the connections D are again moved downward, as a result of the pressure in the tank 10 falling below the predetermined low point, the traveling element d^7 moves into a short section d^4 , encounters the lower end thereof and couples the two parts of the rod b^6 together, so that the further downward movement 15 of the rod causes the collar b^7 thereof to encounter the associated switch lever b^5 of the switch B' before the collar a^7 on the rod a^6 encounters its associated switch lever, and consequently the switch B' is closed and the 20 motor of the pump B is started and continues to run until the pressure in the tank is again restored, when the switch B' becomes closed, and the collar b^8 on the rod b^6 encounters the switch lever b^5 .

25 The switches are, therefore, closed alternately and the pumps started alternately during the successive falls of pressure in the tank. In case the pressure continues to fall below that required to start either of the 30 motors, the lever of the diaphragm device will continue to move downward, thereby moving the connecting device D farther down until the idle upper collar encounters the lever of the open switch and swings said lever down, 35 thereby closing the open switch and starting the motor of the idle pump. When the pressure is again built up to normal, the diaphragm device opens both switches, thereby stopping the motors of both pumps.

40 While the invention has been shown and described in detail in connection with a system operating under pressure, it is to be understood that it is equally applicable to systems operating under vacuum—such obvious 45 minor changes being necessary as to cause the diaphragm device to close a switch when the vacuum on the system needs to be built up. In fact, the invention is applicable to practically all duplex pump systems employing 50 pressure or vacuum in their operation, and while a diaphragm device has been chosen to illustrate a pressure device for actuating the switches, it is to be understood that any pressure or vacuum operated device capable of 55 transferring movement to the switches is included by the term "pressure device".

Furthermore, the specific connecting device shown between the pressure device and switches is for the purposes of illustration 60 only and is only schematic, and that other connections operating to close the switches alternately or in any other sequence is included in the term "connecting device".

Furthermore the connecting device may be 65 employed for actuating the control means

other than electric switches, and the term "pressure" as used herein includes plus pressure and minus pressure or vacuum.

More or less variation of the exact details of construction is possible without departing from the spirit of this invention; I desire, therefore, not to limit myself to the exact form of the construction shown and described, but intend, in the following claims to point out 70 all of the invention disclosed herein. 75

I claim as new and desire to secure by Letters Patent:

1. Mechanism for actuating a plurality of devices in alternate sequence, comprising a pressure device which is responsive to variations of pressure, and motion transmitting connections between said pressure device and the individual devices to be actuated thereby, said connections including alternately acting means for actuating said individual devices 80 in alternate sequence. 85

2. Mechanism for actuating a plurality of devices in alternate sequence, comprising a diaphragm device which is responsive to variations of pressure, and motion transferring connections between said diaphragm device and the individual devices to be actuated thereby, said connections including means for actuating said individual devices 90 in alternate sequence. 95

3. Mechanism for actuating a plurality of electric switches in sequence, comprising a fluid pressure device which is responsive to variations of pressure, and motion transferring connections between said pressure device and the individual switches, said connections including alternately acting means for closing said individual switches in a sequence, and opening the closed switch before 100 another one is closed. 105

4. Mechanism for actuating a plurality of electric switches in sequence, comprising a diaphragm device which is responsive to variations of pressure, and motion transferring connections between said diaphragm device and the individual switches, said connections including alternately acting means for closing said individual switches in alternate sequence. 110

5. Mechanism for actuating a plurality of electric switches alternately, comprising a fluid pressure device which is responsive to variations of pressure, and motion transferring connections between said pressure device and the individual switches, said connections having therein alternately active and inactive connecting members capable of operating consecutively. 115

6. Mechanism for actuating a plurality of electric switches alternately, comprising a diaphragm device which is responsive to variations of pressure, and motion transferring connections between said diaphragm device and the individual switches, said connec- 125 130

tions having therein alternately active switch actuating members.

7. Mechanism for actuating a plurality of electric switches alternately, comprising a diaphragm device which is responsive to variations of pressure, and motion transferring connections between said diaphragm device and the individual switches, said connections having therein a connecting member provided with a variable length stroke.

8. Electric switch actuating mechanism comprising a fluid pressure device responsive to variations of fluid pressure and alternately acting operative connections between said pressure device and the electric switches actuated thereby.

9. Electric switch actuating mechanism comprising a fluid pressure device responsive to variations of pressure, and operative connections between said fluid pressure device and the electric switches actuated thereby, at least one of said connections embodying a variable stroke element, whereby said switches are actuated alternately.

10. Mechanism for actuating a plurality of devices in sequence, comprising a pressure device which is responsive to variations of pressure, and motion transmitting connections between said pressure device and the individual devices to be actuated thereby, said connections including means for actuating said individual devices in alternate sequence and in unison.

11. Mechanism for actuating a plurality of electric switches in sequence, comprising a pressure device which is responsive to variations of pressure, and motion transferring connections between said pressure device and the individual switches, said connections including means for closing said individual switches in alternate sequence and in unison.

12. The combination with two motor controlling switches, of a diaphragm device which is responsive to variations of fluid pressure, and alternately acting motion transmitting connections between each switch and said diaphragm device.

13. The combination with two motor controlling switches, of a diaphragm device which is responsive to variations of pressure, and alternately acting motion transmitting connections between each switch and said diaphragm device capable of acting in unison when the diaphragm device is subjected to abnormal changes of pressure.

14. Mechanism for alternating actuating electric switches of a plurality of electric circuits comprising pressure operated means responsive to variations of pressure, and motion transferring connections between said pressure operated means and said switches, including alternating mechanism for actuating said switches in alternate sequence.

15. Mechanism for alternately actuating electric switches of a plurality of electric cir-

cuits comprising a diaphragm device which is responsive to variations of fluid pressure, and motion transferring connections between said diaphragm device and said switches, including alternating mechanism for actuating said switches in alternate sequence. 70

16. Mechanism for actuating electric switches of a plurality of electric circuits to thereby close the circuits in alternate sequence comprising a pressure operated device which is responsive to variations of fluid pressure, and motion transferring connections between said pressure operated device and said electric switches, including alternating mechanism actuating to close the circuits in alternate sequence, there being means for closing the circuits in succession. 75

17. Mechanism for closing circuits for two electric devices comprising pressure operated means responsive to variations of fluid pressure, electric switches for said circuits, and motion transferring connections between said pressure operated means and said switches, including alternately acting switch tripping mechanism. 80

18. Mechanism for closing circuits for two electric devices comprising pressure operated means responsive to variations of fluid pressure, electric switches for said circuits, and motion transferring connections between said pressure operated means and said switches, including alternately acting switch tripping mechanism, there being means for closing said circuits in succession. 85

19. Mechanism for controlling a plurality of electric circuits comprising a plurality of electric switch units each capable of closing and opening an electric circuit therethrough, pressure operated switch actuating means responsive to variations of pressure, and motion transferring connections between said pressure operated means and said switch units, said connections including alternating mechanism for operating the switch units 90 in alternate sequence to thereby close the circuit through the switch units in alternate sequence. 105

20. Mechanism for controlling a plurality of electric circuits comprising a plurality of electric switch units each capable of closing and opening an electric circuit therethrough, pressure operated switch actuating means responsive to variations of pressure, and motion transferring connections between the pressure operated means and said switch units having switch tripping means for closing a circuit through the switch unit upon one stroke of said motion tripping means and opening the circuit on the return stroke, said connections including alternating mechanism for the switch tripping means to thereby close the circuits through the units in alternate sequence. 110

21. Mechanism for controlling a plurality

of electric circuits comprising a plurality of electric switch units each capable of closing and opening an electric circuit therethrough, pressure operated switch actuating means responsive to variations of pressure, and motion transferring connections between the pressure operated means and said switch units having switch tripping means for closing a circuit through the switch unit upon one stroke of said motion tripping means and opening the circuit on the return stroke, said connections including alternating mechanism for the switch tripping means to thereby close the circuits through the units in alternate sequence, there being means for closing the circuits in succession.

22. Mechanism for controlling a plurality of electric circuits comprising a plurality of electric switch units each capable of closing and opening an electric circuit therethrough, actuating means responsive to variations of pressure, and motion transferring connections between said actuating means and said switch units having switch tripping means for closing a circuit through the switch unit upon one stroke of said motion tripping means and opening the circuit on the return stroke, said connections including alternating mechanism for the switch tripping means to thereby close the circuits through the units in alternate sequence.

23. Control mechanism for alternately closing the electric circuits for two electric motors comprising circuit closing mechanism, one for each circuit, and pressure operated alternate sequence controlling mechanism for the two circuits responsive to variations of fluid pressure in a system, each of said circuit closing mechanisms being capable of also closing an open circuit while the other is closed.

24. In an automatic control system for a plurality of electric motors, the combination of automatically acting starting and stopping mechanism for starting and stopping the operation of the motors, said starting and stopping mechanism being responsive to changes of condition which take place in the system with which the motors are used, and automatic and intermittently acting sequence controlling mechanism co-operating with said starting and stopping mechanism for controlling the sequence of operation of the respective motors, there being means associated with one of said elements for starting an idle motor under an abnormal condition when another motor is in operation.

AUGUSTUS C. DURDIN, JR.
